ATTORNEY

UNITED STATES PATENT OFFICE.

ROBERT E. HESTER, OF WESTMINSTER, COLORADO.

KETTLE-LID.

1,257,229.

Specification of Letters Patent.

Patented Feb. 19, 1918.

Application filed May 5, 1917. Serial No. 166,666.

To all whom it may concern:

Be it known that I, ROBERT E. HESTER, a citizen of the United States, residing at Westminster, in the county of Adams and 5 State of Colorado, have invented new and useful Improvements in Kettle-Lids, of which the following is a specification.

The present invention relates to improvements in tea kettles and such like devices in 10 which water is boiled; and has for its object to provide means whereby the kettle or other device may be readily filled with water while held in the hand without liability of the 15 hand being scalded by the steam from the kettle.

Another object of the invention is to provide a tea kettle or such like device with a closure which is provided with an opening surrounded by an inwardly flared outwardly 20 extending flange, the edge of the opening providing a seat for a substantially cone-shaped valve that is normally under spring tension to retain the same seated, the arrangement being such as to permit of the 25 filling of the kettle without removing the lid therefrom, the kettle being arranged under a faucet which is brought to contact with the valve to move the same to its open 30 position, to permit of the free entrance of water from the faucet to the said kettle.

It is a further object of the invention to provide a lid or closure for kettles or other vessels within which water is boiled that is provided with an opening normally closed 35 by a valve, a hinged arm being connected with the valve which is under the influence of a spring, a bail being secured to the inner face of the lid or closure to provide a directing means for the pivoted arm and also 40 whereby to limit the swinging of the arm in valve opening direction, while means is also provided to regulate the tension of the spring whereby to provide for the contacting relation of the valve with its seat provided by the opening.

With the above and other objects in view the improvement resides in the construction, combination and arrangement of parts set forth in the following specification and falling within the scope of the appended claims.

In the drawing:

Figure 1 is a vertical sectional view through the upper portion of an ordinary tea kettle provided with a lid or closure constructed in accordance with the present 55 invention,

Fig. 2 is a transverse sectional view approximately on the line 2—2 of Fig. 1,

Fig. 3 is a perspective view of the valve and the arm or stem associated therewith.

While it is to be understood that my improvement may be directly applied to the upper portion of a tea kettle or such like articles in which water is to be boiled; I have in the accompanying drawing illustrated the 65 same in connection with a lid or closure for such vessels.

The kettle or vessel is indicated by the numeral 1, and the lid or closure by the numeral 2. The closure may be of any ordinary construction, having the usual flange engaging with the mouth of the kettle 1; and the said closure is preferably of a hollow conical construction, being substantially bell-shaped in cross section. The closure upon its outer surface is centrally provided with the usual handle 3; and the said closure at a suitable distance inward of its flange is provided with a round opening 4. Arranged in the opening 4 and approximately centrally 75 contacting with the wall provided by the said opening is an annular ring or flange 5. This ring or flange is arranged at an inclination with respect to the kettle lid 2, and the inner edge of the said annular member 5 80 provides a seat for a valve 6. The valve preferably comprises a member which is concavo-convex in cross section, and the outer rounded face of the valve is centrally received in the annular member 5. The valve 85 is centrally provided with a rod or stem which is indicated by the numeral 7, the said stem being preferably in the nature of a flat strip of metal which is rounded in plan and the free end of the said stem is pivotally 90 connected, as at 8, to a bracket 9, that is secured to the inner face or surface of the closure 2.

The numeral 10 designates a substantially U-shaped member or bail which is secured in 100 any desired or preferred manner to the under face of the closure 2, the stem 7 of the valve being received between the limbs of the said U-shaped member to prevent the side movement of the said stem and to assure the 105 seating of the valve 6. The inward swinging of the valve is limited by contact of the stem 7 with the connecting member for the limbs of the U-shaped bail 10.

Connected with the stem 7 approximately 110 centrally thereof and to one side of the bail 10 is a helical spring 11, and to the opposite

end of the said spring is secured an adjustable element 12, whereby the tension of the spring 11 may be readily regulated.

The size of the opening 4 is sufficient to at 5 all times permit of the outlet portion or spout of a faucet entering therethrough and contacting with the outer convex face of the valve 6, and the said flow of water will be directed over the said rounded outer face 10 of the valve to freely enter the kettle 1, but at the same time to prevent a free outflow of steam through the opening 4.

The device, it will be noted, provides ample means for protecting the hand of the 15 operator when a vessel is being conveyed to and from the stove.

Having thus described the invention, what I claim is:

1. In a device for the purpose set forth, a 20 lid having a round opening, an annular member centrally secured in the said opening and arranged at an outward angle with respect to the lid, a valve having an outer rounded face contacting with the inner edge 25 of the annular member and having its central bulged portion received in the said annular member, a curved stem for the valve pivotally secured to the lid, and spring means between the stem and the closure for 30 influencing the valve to seat the same.

2. A kettle lid having a round opening, a

flat ring member received in said opening centrally connected to the wall provided by the opening, said ring being arranged at an outward inclination with respect to the lid, 35 a valve having an outer rounded face received in the ring and contacting with the inner edge of the ring, a stem for the valve, a pivotal connection between the stem and lid, and spring pressed means between the 40 stem and lid for normally retaining the valve seated.

3. In a device for the purpose set forth, a kettle lid having a round opening, a flat ring member received in the opening and approximately centrally secured therein, said ring being arranged at an outward inclination with respect to the lid, a valve which is of a concavo-convex cross sectional formation having its outer rounded portion received in the ring and contacting with the inner edge of the ring, an arch-shaped stem for the valve and pivotally connected with the lid, adjustable spring means between the lid and stem for regulating the pressure of 55 the valve against its seat, a bail-shaped guide secured to the lid straddling the stem and designed to prevent the lateral movement of the stem and to limit the inward swinging movement of the said stem. 60

In testimony whereof I affix my signature.
ROBERT E. HESTER.
